UNITED STATES PATENT OFFICE.

WILLIAM R. PRIEST, OF PHILADELPHIA, PENNSYLVANIA.

CHAIR-SUPPORTING TRUCK.

1,186,940.

Specification of Letters Patent. Patented June 13, 1916.

Application filed August 16, 1915. Serial No. 45,779.

To all whom it may concern:

Be it known that I, WILLIAM R. PRIEST, a citizen of the United States, residing at Philadelphia, in the county of Philadelphia and State of Pennsylvania, have invented 5 certain new and useful Improvements in Chair-Supporting Trucks, of which the following is a specification.

My invention relates to improvements in 10 chair supporting trucks, the object of the invention being to provide a truck which is especially adapted for the support of a rocking chair, so that an invalid can be readily moved from place to place, either 15 by pushing the chair or pulling the same by means of a handle, the latter operating as a tray support when at rest.

A further object is to provide an improved truck of the character stated which 20 can be adjusted so as to fit any ordinary rocking chair, which will be of extremely simple inexpensive construction, which will be strong and durable, and which most efficiently performs the functions for which it 25 is intended.

With these and other objects in view, the invention consists in certain novel features of construction and combinations and arrangements of parts as will be more fully 30 hereinafter described and pointed out in the claims.

In the accompanying drawings: Figure 1 is a view in side elevation illustrating my improvements. Fig. 2 is a view in front 35 elevation with the chair and table removed, the rockers of the chair being shown in dotted lines. Fig. 3 is a sectional plan view. Fig. 4 is an enlarged fragmentary view in longitudinal section through one 40 of the rocker supporting bearing brackets. Fig. 5 is a detail view illustrating the pivotal mounting of the handle, and Fig. 6 is a fragmentary view in section illustrating the table and its supporting handle 45 bar.

My improved chair supporting truck comprises two parallel axles 1 and 2, to which a U-shaped frame 3 is secured, said frame preferably comprising a casting having recesses to receive the shafts and se-

cured by rivets 4 or otherwise to the shafts. The shafts 1 and 2 are supported in bearing brackets 5, one of which is shown in section in Fig. 4. Each bearing bracket 5 has aligned bearings 6 and 7 spaced apart and 55 connected by an arch 8, which extends over the wheel 9 mounted to turn on the axle. The inner bearing 7 is provided with a set screw 10, which jams against the axle and permits the adjustment of the bearing 60 bracket as desired. The outer bearing bracket 6 has a smooth or flat upper face 11 to receive and support the rocker 12 of an ordinary chair 13, and an upwardly projecting lug 14 on the extreme outer end of 65 the bearing 6 acts to confine the rocker between the same and the arch 8.

The above description of one bearing bracket applies alike to all four, so that four wheels preferably rubber tired, and 70 preferably relatively small, are provided to support the frame and the chair, and permit the latter to be readily moved from place to place.

When a chair is in position on the truck, 75 the natural curve of the rockers compel the bearing brackets to assume an angle relative to the floor, and the lugs 14 are preferably rounded on their inner faces as clearly shown in Fig. 3, so as to readily 80 accommodate the brackets to the shape of the rocker, and yet snugly hold the same.

It will be noted that when the rockers are in place, if the bearing brackets are adjusted outwardly as far as possible, or inwardly as far as possible, the rockers will be securely gripped, and there can be no possibility of accidental displacement.

At the front of the frame 3, upwardly projecting parallel ears 15 are provided, 90 and support a handle 16 which is pivotally connected to the ears by a bolt or rivet 17, and the lower end of said handle 16 is beveled as shown at 18 to engage a beveled block 19 and limit the inward pivotal movement 95 of the handle. The upper end of the handle curves inwardly, and is normally horizontal, and at its extreme end is provided with a horizontal handle bar 20 which is adapted to support a table 21. This table 100

21 is removably connected to the handle, and while of course I am not limited to the particular manner of connecting the same to the handle, I have shown lugs 22 on the 5 bottom of the table which project through openings 23 in the handle 20.

It will be noted that with my improvements the chair can be readily moved about by pushing upon the back of the chair so 10 as to move an invalid about the room or along the street as desired.

If it is desired to pull the chair rather than push it, the table 21 can be removed and the handle swung downwardly as indicated in dotted lines in Fig. 4, and by 15 gripping the handle bar 21, the chair can be pulled wherever desired.

At the forward end of the frame 3, a cross bar 24 is located, and constitutes a 20 foot rest, although the other forms of foot rest may be provided as desired.

My improved truck is adapted for use with any ordinary rocking chair, and can be furnished at a reasonably low price, so 25 that an invalid chair can be made with but slight expense.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

35 Having thus described my invention, what I claim as new and desire to secure by Letters Patent is:

1. A chair supporting truck, comprising axles, bearing brackets adjustable on the 40 axles, wheels supporting the axles and bearing brackets, and said bearing brackets constructed to support a chair thereon, substantially as described.

2. A chair supporting truck, comprising 45 axles, bearing brackets adjustable on the axles, wheels supporting the axles and bearing brackets, said bearing brackets having flat upper faces, and lugs at their outer ends adapted to confine the rockers of a chair on said flat faces, substantially as described.

3. A chair supporting truck comprising parallel axles, four bearing brackets adjustable on the axles, each bearing bracket comprising two bearings spaced apart and an 55 integral arch connecting the bearings, wheels on the axles between the bearings of the brackets, upwardly projecting lugs on the outer ends of the bearing brackets, and each bearing bracket having a flat rocker supporting face between its arch and its 60 upwardly projecting lug, substantially as described.

4. A chair supporting truck comprising parallel axles, four bearing brackets adjust-

able on the axles, each bearing bracket comprising two bearings spaced apart and an integral arch connecting the bearings, wheels on the axles between the bearings of the brackets, an upwardly projecting lug on the outer end of the bearing brackets, 65 and each bearing bracket having a flat rocker supporting face between its arch and its upwardly projecting lug, set screws carried by the inner bearings and adapted to jam against the axles, and a frame connecting the axles, substantially as described.

5. A chair supporting truck, comprising axles, bearing brackets adjustable on the axles, wheels supporting the axles and bearing brackets, and said bearing brackets constructed to support a chair thereon, a frame connecting the axles, a handle pivotally connected to the forward end of the frame, and at its free end projecting rearwardly, a handle bar on the free end of the handle, 85 and a table removably supported on the handle bar, substantially as described.

6. A chair supporting truck, comprising axles, bearing brackets adjustable on the axles, wheels supporting the axles and bearing brackets, said bearing brackets having flat upper faces, lugs at their outer ends adapted to confine the rockers of a chair on said flat faces, a frame connecting the axles, a handle pivotally connected to the 95 forward end of the frame, and at its upper end projecting rearwardly, a handle bar on the free end of the handle, and a table removably supported on the handle bar, substantially as described.

7. A chair supporting truck comprising parallel axles, four bearing brackets adjustable on the axles, each bearing bracket comprising two bearings spaced apart, an integral arch connecting the bearings, a wheel 105 on the axle between the bearings, an upwardly projecting lug on the outer end of the bearing bracket, each bearing bracket having a flat rocker supporting face between its arch and its upwardly projecting lug, 110 a frame connecting the axles, a handle pivotally connected to the forward end of the frame, and at its upper end projecting rearwardly, a handle bar on the free end of the handle, and a table removably supported on the handle bar, substantially as described.

8. A chair supporting truck comprising parallel axles, four bearing brackets adjustable on the axles, each bearing bracket comprising two bearings spaced apart, an integral arch connecting the bearings, a wheel 120 on the axle between the bearings, an upwardly projecting lug on the outer end of the bearing bracket, each bearing bracket having a flat rocker supporting face between its arch and its upwardly projecting lug, a frame connecting the axles, a handle pivotally connected to the forward end of

the frame, and at its upper end projecting rearwardly, a handle bar on the free end of the handle, a table removably supported on the handle bar, means limiting the rearward pivotal movement of the handle, and 5 a foot rest on the frame in advance of the front axle, substantially as described.

In testimony whereof I have signed my name to this specification in the presence of two subscribing witnesses.

WILLIAM R. PRIEST.
